UNITED STATES PATENT OFFICE

DONALD S. BARROWS, OF ROCHESTER, NEW YORK, ASSIGNOR TO THE SYMINGTON COMPANY, OF NEW YORK, N. Y., A CORPORATION OF MARYLAND

CAR TRUCK

Application filed September 14, 1926. Serial No. 135,430.

This invention relates to railway car trucks and, more particularly, to cast frames therefor of unusually rigid construction and formed either with associated journal boxes or adapted for being rigidly connected thereto.

The principal object of my invention, generally considered, is the provision of car trucks formed with side frames in which the bolster guide columns, at the lower portions thereof, are rigidly connected by an integral bridge or girder extending longitudinally of the frame and dividing the spring plank seat portion into two parts, said girder, if desired, being formed with an aperture adapted to receive an extension from an associated spring plank for the more rigid connection of said spring plank to the frame, the bolster used with said truck being normally freely insertable between the bolster guide columns above the bridge and locked in place by means of bolster blocks inserted between the sides of the bolster and the columns before the bolster springs are placed in position.

An object of my invention is the provision of what may be designated as a girder type side frame, said side frame being formed with a window opening partially closed by an upright longitudinal bridge wall or girder joining the lower portions of the bolster guide columns and extending from the spring plank seat portion of the tension member, an aperture in said girder being alternatively provided for receiving an end of an associated spring plank.

Another object of my invention is the provision of a side frame formed with a bridge wall extending from the spring plank seat portion and between the struts or bolster guide columns, thereby restricting the bolster opening, and means for locking the bolster in place above said bridge wall before the bolster springs are inserted in place, said means comprising blocks insertable between said bolster columns and bolster and provided with portions engaging in bolster slots and other portions embracing the adjacent portions of the bolster guide columns, said blocks being retained in proper position by base por-

tions extending inwardly beneath the bolster and above the bolster supporting springs.

A further object of my invention is the provision of a cast side frame formed with a rigidifying hollow bridge wall joining the lower portions of the bolster guide columns, which lower portions are flared to the diagonal portions of the tension member, the bolster springs being positioned on the intermediate portion of the tension member on both sides of the hollow bridge wall and inserted in place after the bolster has been positioned between the bolster guide columns and locked in place by removable blocks inserted to the side and below said bolster and supported on a spring plate covering all of said springs and with its upper surface in one plane, such construction permitting the shimming of the springs to preserve the coupler height by a simple block shim above the spring plate.

A still further object of my invention is the provision of an unusually strong side frame in which a relatively small bolster opening is provided, thereby permitting a frame of increased depth below the bolster opening, the bolster being held in place by readily removable locking blocks thereby permitting easy removal of the parts.

An additional object of my invention is the provision of a cast side frame formed with rigid jaw shaped portions at the ends thereof adapted to embrace or connect with associated journal boxes, said jaws being designed with a cross section varying outwardly from box to H shape for efficient utilization of the metal forming said frame.

Other objects and advantages of the invention relating to the particular arrangement and combination of the various parts will become apparent as the description proceeds.

Referring to the drawings illustrating my invention, the scope whereof is defined by the appended claims:

Figure 1 is a partial side elevation of a truck illustrating one embodiment of my invention, a portion of a side frame thereof being shown in central longitudinal section.

Figure 2 is a plan of one half of the side

frame and a portion of the associated bolster and connecting means therebetween illustrated in Figure 1.

Figure 3 is a transverse section on the line 5 3—3 of Figure 1 looking in the direction of the arrows.

Figure 4 is a detailed sectional view on the line 4—4 of Figure 1 looking in the direction of the arrows.

10 Figures 5, 6 and 7 are partial sectional views on the correspondingly numbered lines of Figure 1 looking in the direction of the arrows.

15 Figures 8, 9 and 10 are detailed sections on the correspondingly numbered lines of Figure 1.

20 Figure 11 is a partial diagrammatic illustration of the side frame shown in Figure 1 in the vicinity of the bolster opening to illustrate how the bolster is locked in place by means of locking blocks embodying my invention.

25 Figure 12 is a fragmentary sectional view on the line 5—5 of Figure 1 but differing from Figure 5 in that it shows a portion of the bolster and one associated locking block in position.

30 Figure 13 is a fragmentary elevation corresponding to Figure 1 but showing a modification.

Fixtures 14 and 15 are sectional views on the correspondingly numbered lines of Figure 13 looking in the direction of the arrows.

35 Figure 16 is a partial diagrammatic view corresponding to Figure 13 to illustrate the application of the modified locking blocks between the bolster and bolster guide columns.

40 Referring to the drawings in detail and first considering the embodiment of my invention illustrated in Figures 1 to 12, inclusive, a truck side frame 1 of the cast type is shown although it will be obvious that certain advantages of my invention may be secured using frames of other than cast construction. Said frame 1 comprises a compression member 2, a tension member 3, and bolster guide columns or strut portions 4, spacing intermediate portions of said compression and tension members, leaving a bolster or window opening 5 therebetween. The compression and tension members are joined to each other and to a jaw shaped portion 6 adjacent each end of the frame, which portions 6 are either adapted to embrace and be connected with associated journal boxes (not shown) or, if desired, may be formed integral with such journal boxes.

45 For rigidifying the construction of the frame, the lower portions of the bolster guide columns 4 are preferably rigidly connected by means of a bridge wall or girder 7, said girder, in the present embodiment, being formed with two vertical web portions 8 connected at the top by a transverse web por-

tion 9, said girder 7 extending from the upper web 10 of the intermediate or horizontal portion 11 of the tension member 3. The bolster guiding portions of the bolster guide columns 4, at opposite ends of the bridge wall 7, which columns are substantially channel shape in cross section, are preferably flared outwardly from the top of the girder 7 to the tension member 3 where they connect with said tension member either substantially perpendicular therewith or the outer edges of the flanges of said section extend at substantially this angle with respect thereto, as shown particularly in Figure 1. On account of this construction, the upper web 10 of the horizontal portion of the tension member is formed of ample length for supporting spring units 12 positioned three in longitudinal alignment on each side of the bridge wall 7. For the purpose of properly supporting an associated spring plank 13 and six spring units 12, the web 10 of the tension member is widened on opposite sides of the girder 7 and provided with spring and spring plank lugs or bosses 14.

50 Although an A. R. A. bolster might be adapted for use with a frame of the general character disclosed yet, on account of the double bridge wall or girder between the bolster guide columns and the increased spring capacity provided by six spring units, it is preferable to make the bolster 15 somewhat longer than normal although it may be of standard width and provided with standard bolster guide notches 16. The bolster guiding portions of the columns 4 are spaced wider than normal so that a bolster of standard width is insertable therebetween without vertical movement as will be apparent from a consideration of Figures 11 and 12 particularly. It will be noted that the transverse portion 17 of the bolster guiding web is formed with diagonal side portions or wings 18 providing a guide surface with flaring side portions rather than parallel side portions. After insertion in place, as illustrated particularly in Figure 12, the bolster may be locked in position by means of blocks 19 initially inserted in horizontal position, as illustrated in Figure 11, and moved from such position to vertical position between the bolster 15 and bolster guiding portions 17 and 18 of the bolster columns through intermediate diagonal positions, indicated diagrammatically by dot and dash lines, before the bolster springs and spring plate are inserted in position and while the bolster is elevated to the upper portion of the bolster opening 5.

55 In the embodiment illustrated, my bolster locking blocks 19 are formed with an inner sloping face 20 insertable in a correspondingly notched portion of the bolster, said face terminating at its lower edge in a base flange 21 fitting in the correspondingly notched por-

tion in the bolster. The outside portion of the blocks 19 are formed with transverse faces 22 adapted to engage the transverse web portion 17 and diagonal faces 23 on opposite sides thereof adapted to engage the diagonal web portions 18 of the bolster guide columns. The angle or slope of the face 20 is such that the blocks may be moved from horizontal position into place between the bolster and bolster guide columns where a relatively snug fit is provided therefor so that said bolster is retained or locked in proper assembled relation with respect to the frame. The base flange 21, as will be apparent, serves to support its block in proper assembled relation by resting on the spring plate or cap 24 between the same and the bolster.

For economy of material and for lightening the weight of the side frame, substantially triangular apertures 25 may be provided in the webs 8 of the bridge wall or girder 7 and the upper web or wall of the tension member or spring plank seat portion thereof may be omitted between the webs 8, as most clearly shown in Figures 1 and 3. For the same reason, relatively large openings 26 may be provided in the lower web 27 of the tension member 3, the side walls or inner and outer webs 28 and 29 being tied together by transverse web portions 30 and the edges of the lower web 27 are preferably rigidified by depending ribs or beading 31. Intermediate the transverse web portions 30 and preferably in line with spring plank and spring bosses 14 are triangular shelf or web portions 32 between the webs 28 and 29 of the tension member and the portions of the upper web 10 or spring plank seat portion beyond said webs, thereby serving for adequately supporting the same.

The girder or bridge wall 7 is preferably continued or extended beyond the bolster guide columns 4 or flaring lower portions thereof, the webs 8 of said wall preferably being separated forming bifurcated end portions 33 which flare outwardly at the same time decreasing in depth until they merge with the upper web of the diagonal end portions of the tension member 3 in line with the side webs 28 and 29 thereof. The upper connecting web 9 is omitted from substantially the beginning of the flared portions 33 although said flared portions are preferably in lieu thereof provided with inwardly extended beading 34 along the upper edge thereof. These extended web portions of the bridge wall 7 are preferably provided with a drainage opening 35 and a substantial aperture 36 is preferably provided in the upper web of the tension member 3 beneath said drainage opening and between the extended portions 33.

The compression member 2 is preferably inverted U shape in cross section and beyond the bolster guide columns 4 is flared slightly

to increase the same in depth to where it joins with the jaw shaped portions 6 over the journal boxes and the tension member. At the same time, the compression member 2 is preferably sloped downward and outward to meet the tension member 3 which is sloped upward and outward, said tension member 3 being preferably substantially U shape in cross section so that, upon meeting, they form a section substantially box shape in cross section. Such a section, however, is not the most economical for the ends of the jaw shaped portions 6 of the frame so the side webs 37 and 38 are preferably caused to converge inwardly, while the top and bottom webs are only slightly tapered, and join a short distance beyond the center line of the jaw portion to form the single longitudinal web 39 of the outer jaw end, thereby causing the section of the jaws 6 to change from box to substantially H or I shape in cross section. The lower end of each jaw portion preferably tapers and the outer jaw section of each jaw is preferably provided with a horizontal aperture 40 which may serve to receive locking means for holding an associated journal box in position. The inner jaw portion 41, in the present embodiment, is shown substantially U shape in cross section rather than H or I shape in cross section and is merely formed as a downward projection from the lower web of the corresponding diagonal end of the tension member. Although said lower web is preferably curved around the jaw over the associated journal box, provision may be made for a substantial bearing area between the jaw and the flat top of the journal box by longitudinal and transverse ribbing 42 extended from the lower web or flange of the section and formed with the lower edges thereof substantially horizontal or lying in the same plane. The rounded jaw ends may be continued for strengthening the jaw portions 6 by internal curved webs or beads 43 serving to unite the inner jaw portion 41 with the corresponding outer jaw portion as will be understood. If desired, transverse, preferably triangular, bracing webs 44 may be formed between the lower web or flange 45 of the jaw and the main upright web 39 thereof.

Referring now to the modification of my invention illustrated in Figures 13 to 16, inclusive, I have there shown a side frame 1^a of a construction very similar to that of the side frame 1 of the first embodiment except that the bridge wall or girder portion 7^a is formed with a preferably substantially triangular aperture 46 extending from the spring plank seat portion 10^a of the frame upwardly a sufficient distance and longitudinally a sufficient width for receiving an extension 47 from the spring plank 13^a, said extension being of a sufficient width for sup-

70

80

85

90

95

100

110

115

120

125

130

porting one outer spring unit of group 12^a. The aperture 46 is not of a sufficient size to materially destroy the effectiveness of the bridge wall 7^a but may be considered as merely 5 taking the place of the lightening apertures 25 of the first embodiment. Such a construction, however, provides for more securely connecting the spring plank 13^a with the side frames as it is adapted to extend over 10 and connect with four instead of only three spring plank lugs 14^a and is held securely against the spring plank seat portion by four rather than only three spring units 12^a.

Although I may employ a bolster and 15 bolster connecting blocks identical with that used with the first embodiment, yet, as an alternative, I may employ the bolster locking blocks 48 which are provided with portions 49 adapted to engage in bolster notches 20 16^a and are also provided with locking surfaces 22^a and 23^a corresponding with the locking surfaces 22 and 23 of the first embodiment and serving for engaging the corresponding walls 17^a and 18^a of the bolster 25 guide columns 4^a. The manner of insertion of the locking blocks 48 is, however, different from that of the locking blocks 19 because said blocks 48 are not tilted to a horizontal position before insertion but are rather lowered over the bridge wall 7^a while the bolster 15^a is correspondingly raised. For that purpose, said locking blocks are provided with 30 notched portions 50 allowing them to telescope with, embrace or straddle the bridge 35 wall 7^a so as to permit a substantially lowering thereof or lowering to an amount sufficient to permit the placing beneath the bolster, as shown in Figure 16, before the springs are placed in position, after which said locking 40 blocks are raised to extend between the bolster and bolster guide portions of the frame and lock said bolster in proper assembled relation.

As in the first embodiment of my invention, the locking blocks 49 are provided with 45 base flanges 51 adapted to extend in corresponding notches in the bolster and normally be secured between said bolster and the spring plate 24^a. After the blocks have been inserted 50 in position, the spring plate may be assembled therebeneath and the springs inserted one at a time between said spring plate, spring plank and spring seating portion of the frame. Except as specifically described 55 in connection with this second embodiment of my invention, the same may be substantially identical in construction and operation as that of the first embodiment. It will also be understood that although I have shown 60 locking blocks 19 used with the first embodiment and differently constructed locking blocks 48 used with the second embodiment, yet, if desired, either type of locking blocks and the corresponding bolster may be employed with either type of side frame.

In accordance with the foregoing disclosure, it will be apparent that I have devised an improved car truck and associated side frame in which increased spring capacity has been provided while, at the same time, the 70 maintenance of the required coupler height has been allowed for by a very simple shimming operation, because a flat shim may be applied between two flat surfaces, that is, between the top of the spring plate and the 75 bottom of the bolster and locking blocks, instead of beneath the springs. One of the main advantages, however, of the construction is that the strength of the frame is very 80 materially increased by the longitudinal girder or double bridge wall joining the lower flaring portions of the bolster guide columns. This bridge wall not only strengthens the frame but is preferably formed of such a height that it limits the downward 85 movement of the bolster so as to prevent the bolster springs from being compressed solid with the consequent danger of breakage. Although I have shown but two embodiments 90 of my invention, both of which employ six spring units, it is obvious that great variety in spring capacity may be provided for, either by forming all of said spring units single or double or some single and some double in any desired arrangement, or a different 95 number of spring units may be employed.

A preferred method of assembling the bolster with respect to the side frame is as follows. With the spring plank in place 100 before the springs are inserted, the bolster is inserted between the bolster guide columns and maintained in the upper part of the window opening while the locking blocks are positioned so as to straddle the bridge wall 105 either as shown in Figure 11 or in Figure 16 depending on the type of locking block used. The locking blocks may then be raised to position between the sides of the bolster and the adjacent bolster guide column, the spring 110 plate inserted in place therebeneath and the springs inserted beneath said spring plate above the spring plank and spring seating portions of the frame. The spring plate, bolster and bolster locking blocks or shoes 115 may then be lowered upon the springs to the positions indicated in Figures 1, 3, 13 and 14 particularly. It will be apparent that such an assembly may be rapidly made with very little trouble and the elements, when assembled, may be taken apart in the reverse order.

Having now described my invention, I claim:

1. A side frame comprising a compression member, a tension member, bolster guide columns interposed between said compression and tension members and spaced to leave a window opening, those portions of the tension member, beyond the bolster guide columns, extending diagonally upward and 125 130

outward to join with the compression member adjacent the ends thereof, and a girder connecting the lower portions of said bolster guide columns, those portions of the bolster guide columns, beneath the top of the girder, being deflected outwardly and downwardly to meet the diagonal portions of the tension member at substantially right angles.

2. A side frame comprising a compression member, a tension member, bolster guide columns positioned therebetween and spaced apart to leave a bolster opening, the lower portions of said bolster columns, beneath the bolster opening, being flared downwardly and outwardly to join with the end portions of the tension member and connected together by a longitudinally extending girder portion.

3. A side frame comprising a compression member, a tension member, struts interposed therebetween and spaced to leave a bolster opening, said compression and tension members being generally U shape in cross section and united at their ends to a downwardly opening jaw shaped portion of the frame adapted to connect with an associated journal box, said jaw shaped portion being generally box shape in cross section from the intersection of the compression and tension members to beyond the center line of the associated journal box, said jaw portion there gradually changing from box to H section by the side webs thereof converging and merging to form a central longitudinal web.

4. A side frame comprising a compression member, a tension member, bolster guide columns interposed therebetween and spaced apart to leave a bolster opening, said compression member being generally inverted U shape in cross section and the tension member being generally U shape in cross section and joining with the compression member adjacent the ends thereof to form a jaw portion adapted to connect with an associated journal box, said jaw portion, by virtue of the emergence of the compression and tension members, being generally box shape in cross section to beyond the center line of the associated box where the side webs of said section converge inwardly to form a central longitudinal web and the section changes from box to H shape.

5. A side frame comprising a compression member, a tension member, struts interposed therebetween and spaced to leave a bolster opening, and a bridge wall connecting said struts beneath the bolster opening, said bridge wall being continued through said struts, bifurcated and flared outwardly toward the tension member, the bifurcated portions of said bridge wall decreasing in depth and finally merging with the end portions of the tension member.

6. A side frame comprising a compression member and a tension member spaced at intermediate portions thereof by bolster guide

columns, leaving a window opening therebetween, said tension member, on the opposite sides of said bolster guide columns, extending diagonally outward and upward, meeting the compression member, that portion of the tension member, beneath the window opening, being laterally widened for supporting a spring plank and bolster springs, and a bridge wall connecting said bolster guide columns above said spring plank and spring supporting portion of the tension member, said bridge wall being formed as two webs united at the top and continued through and beyond said bolster guide columns, the webs of said bridge wall, beyond the columns, separating, flaring outwardly and uniting with the diagonal portions of the tension member in line with the side walls thereof, the depth of said separated portions gradually decreasing until the bridge wall merges with the tension member.

7. In a car truck, in combination, a side frame formed with compression and tension members spaced at intermediate portions thereof by bolster columns leaving a bolster opening therebetween, the tension member, beneath the bolster opening, being formed with a spring seating portion and a longitudinally extending upright web joining the lower portions of the bolster columns and dividing the spring seating portion, said web serving to strengthen the frame and being of such a height as to limit downward movement of the bolster and prevent the springs from going solid, a bolster associated with said frame and adapted for direct insertion into the bolster opening above the web, and means positioned between the bolster and bolster columns for retaining said bolster in place and adapted to be moved to releasing position between said bolster and web.

8. In a car truck, in combination, a side frame formed with a compression member, a tension member, struts interposed therebetween and spaced to leave a bolster opening, a bridge wall connecting said struts below the bolster opening, that portion of the tension member, beneath the bolster opening on opposite sides of the bridge wall, being adapted for supporting bolster springs, bolster springs supported on said portion of the tension member, a bolster supported thereabove by means of said bolster springs, said bolster being of such a size that it is freely insertable between the struts, and blocks positioned above the springs and held in place between the bolster and struts to lock said bolster in place, said blocks being adapted for movement to release position between said bolster and wall.

9. In a car truck, in combination, a side frame formed with a compression member, a tension member, bolster guide columns interposed therebetween and spaced to leave a bolster opening, a bridge wall connecting said

struts below the bolster opening, bolster springs supported on portions of the tension member on opposite sides of the bridge wall beneath the bolster opening, a bolster supported by means of said bolster springs, said bolster being freely insertable between the struts and formed with notched adjacent said struts, and locking blocks insertable in said notches between said bolster and bolster guides and provided with portions extending inwardly between said bolster and springs to hold said blocks in proper assembled position, said blocks serving to lock the bolster in place and being notched to fit over said bridge wall and permit movement to inoperative positions between said bolster and wall.

10. In a car truck, in combination, a side frame formed with a compression member, a tension member, bolster guide columns interposed therebetween and spaced to leave a bolster opening, a girder portion connecting said bolster guide columns beneath the bolster opening, bolster springs supported on the tension member on opposite sides of said girder extending thereabove, a spring cap positioned over all of said springs, a bolster supported on said spring cap, said bolster being freely insertable between the bolster guide portions and provided with notches adjacent said guide portions, and bolster shoes positioned between said columns and bolster engaging in said notches and provided with portions embracing said bolster columns to lock the bolster in place, said shoes being also provided with base portions extending beneath said bolster and above said spring cap to hold said shoes in proper position, said shoes being insertable and removable from between said bolster and guide columns when the springs are out of position and adapted to embrace the upper portion of said girder portion to permit movement of said shoes to releasing positions between said bolster and girder portion.

45. 11. In a car truck, in combination, a side frame formed with a compression member, a tension member, struts interposed therebetween and spaced to leave a bolster opening, a bridge wall connecting said struts below the bolster opening, bolster springs supported on portions of the tension member on opposite sides of the bridge wall, a spring plate positioned above said springs, a bolster supported on said spring plate and adapted for being held at an adjusted height with respect to said plate and locking blocks positioned between said struts and the adjacent sides of the bolster and provided with portions underlying said bolster for holding said blocks in place and adapted to be dropped into telescoping relation with said wall for releasing said bolster.

60. 12. In a car truck, in combination, a side frame formed with compression and tension members spaced at intermediate portions

thereof by bolster columns, leaving a bolster opening therebetween, the tension member, beneath the bolster opening, being formed with a spring plank seat portion and a longitudinally extending upright web joining the lower portions of the bolster columns and dividing the spring plank seat portions, said web serving to strengthen the frame and adapted to limit downward movement of the bolster, a spring plank supported on a portion of said spring plank seat portion and springs supported on said spring plank and the remainder of said spring plank seat portion, a bolster supported by means of said springs above said web and locked in place with respect to said frame by removable blocks insertable between the bolster and bolster columns.

70. 13. In a car truck, in combination, a side frame formed with a compression member, a tension member, struts interposed therebetween and spaced to leave a bolster opening, a bridge wall connecting said struts below the bolster opening, that portion of the tension member, beneath the bolster opening on opposite sides of the bridge wall, serving as a spring plank seat portion, a spring plank connected to said spring plank seat portion and covering a portion thereof, bolster springs supported on said spring plank and spring plank seat portion, the spring plate positioned above said springs and a bolster supported on said spring plate, said bolster being locked in place between the struts by removable blocks positioned between said bolster and struts before the springs are inserted in place.

75. 14. In a car truck, in combination, a side frame formed with a compression member, a tension member, bolster guide columns interposed therebetween and spaced to leave a window opening, a girder connecting said bolster guide columns beneath the window opening, that portion of the tension member, on opposite sides of the girder, forming a spring plank seat portion, a spring plank supported on said seat portion and said girder being formed with an aperture for receiving an extension of said spring plank, bolster springs supported on said spring plank on both sides of the girder and additional springs supported on the remainder of the spring plank seat portion, all of said springs extending above the girder and adapted to support an associated bolster.

80. 15. A side frame comprising a compression member, a tension member, bolster guide columns interposed therebetween and spaced to leave a bolster opening, and a bridge wall connecting said bolster guide columns beneath the bolster opening, said bridge wall extending from the top of the tension member and provided with an opening extending from said tension member and serving to receive an associated spring plank, said ten-

125

130

sion member being widened beneath the bolster opening for supporting bolster springs on both sides of said wall.

16. A side frame comprising a compression member, a tension member, bolster guide columns positioned therebetween and spaced apart to leave a bolster opening, the lower portions of said bolster guide columns being connected by a longitudinally extending wall
 10 serving to strengthen the frame, said wall extending from the upper portion of the tension member, said portion of the tension member being laterally widened to serve as a spring plank seat and spring supporting
 15 portion, a substantially triangular opening being provided through the central portion of said wall adjacent the seat for receiving a portion of an associated spring plank.

17. A bolster locking block comprising an
 20 upright portion adapted for positioning between the side of a bolster and the adjacent bolster guide column and formed with a notch the sides of which are beveled for receiving said column and a portion adapted
 25 for reception in a corresponding bolster notch and means for holding said block in proper assembled relation with respect to said bolster.

18. A bolster locking block comprising an
 30 upright portion adapted for insertion, from below, between a bolster guide column of a side frame and the adjacent side of the bolster, said portion being formed with a notch adapted to engage said column and with a
 35 guide portion adapted to engage in the corresponding bolster notch and a base portion adapted to engage in a notched portion of the bolster above the bolster supporting means to hold said block in proper assembled relation,
 40 said upright portion flaring downwardly to meet the base portion.

19. The method of locking a bolster in proper position with respect to an associated side frame, having a bridge wall connecting
 45 the lower portions of the bolster guide columns and restricting the bolster opening, comprising inserting said bolster between said bolster guide columns with locking blocks positioned therebeneath and resting
 50 on their sides on the bridge wall, rotating said locking blocks until they rest with their bases on the wall with one block between each side of the bolster and the adjacent bolster guide column, positioning a spring plate
 55 beneath said bolster and locking blocks, positioning bolster springs beneath said spring plate in proper assembled relation and finally lowering said bolster, bolster locking blocks and spring plate upon said springs.

60. 20. A bolster locking block comprising a normally upright portion adapted to be positioned between the side of a bolster and the adjacent bolster guide column and formed with a notch the sides of which flare away
 65 from each other for receiving said column,

a portion adapted for reception in a corresponding bolster notch, and a base portion adapted to engage in a correspondingly notched portion of the bolster and be positioned above the bolster supporting means
 70 to hold said block in proper assembled relation, said normally upright portion gradually decreasing in thickness from the base portion to the top thereof.

In testimony whereof I affix my signature. 75
 DONALD S. BARROWS.
